UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF MISSOURI.

CAR-ROOF.

1,078,967.

Specification of Letters Patent. Patented Nov. 18, 1913.

Application filed October 18, 1911. Serial No. 655,311.

To all whom it may concern:

Be it known that I, VICTOR M. SUMMA, residing at St. Louis, Missouri, and being a citizen of the United States, have invented 5 certain new and useful Improvements in Car-Roofs, of which the following is a full, clear, and exact description, such as will enable others skilled in the art to which it app- pertains to make and to use the same, refer- 10 ence being had to the accompanying drawings, which illustrate the preferred form of the invention, though it is to be understood that the invention is not limited to the exact details of construction shown and described, 15 as it is obvious that various modifications thereof will occur to persons skilled in the art.

In said drawings: Figure 1 is a top plan view of a portion of a car roof constructed 20 in accordance with this invention, one-half of said roof being illustrated with the roof plates removed. Fig. 2 is an enlarged trans- verse sectional view through the roof, taken on the plane of line 2—2 of Fig. 1. Fig. 3 25 is a fragmentary sectional view enlarged from a portion of Fig. 2 for better illustrating the connections between the sections of the roof and the manner of attaching the running board saddles. Fig. 4 is a longitudi- 30 nal sectional view of one of the end portions of the roof, said section being taken on the plane of line 4—4 of Fig. 1, and Fig. 5 is a detail view, partly in section, illustrating the manner of attaching the ends of the 35 carlines to the wall plate.

The object of this invention is to provide a substantial roof structure comprising a minimum number of parts, and each of said parts being of simple design for facilitating 40 ease of manipulation.

A further object is to so dispose the connections between the several roofing plates, and between the roofing plates and the purlins, that the adjacent portions of the plates 45 will serve to greatly reinforce the purlins and thus render possible the use of purlins of less cross sectional area than would be otherwise required.

Referring to the drawing, the numerals 50 1—1 indicate the side posts of the car structure and 2—2 the sheathing plates applied to the outer faces thereof. The longitudinally extending side plates as 3—3, fixed to the upper ends of the posts 1, may comprise 55 any desired cross section but are preferably

of Z shape, being disposed with their webs horizontal and with inner flanges 4 upstanding from said webs, and with outer flanges 5 depending. The upstanding flanges 4 are preferably fixed to the outer faces of the upper edges of the sheathing plates 2 by through rivets, some of which extend through the flanges of posts 1.

The carlines 6—6 are illustrated as comprising simple angle sections, each with one 65 of its flanges disposed horizontal and its other flange depending. Said carlines may however, be formed of any desired cross section. Each of the carlines extends continu- 70 ously from side wall to side wall, being bent 75 at its middle point for inclining its opposite ends downwardly as is customary. The opposite end portions as 6^a—6^a extend over and beyond the upper edge of the sheathing plates 2 and are bent vertically downward, 80 outside of said plates, so that their extreme ends rest squarely upon the upper surfaces of the webs of the side plates 3. One of their flanges is extended and bent to a horizontal as at 7 and riveted to the upper surface of 85 the side plate. Only two purlins are em- ployed and these as 8—8, are fixed to the carlines at points spaced equi-distant upon opposite sides of the longitudinal median line of the roof. Each of the purlins 8 com- 90 prises an angle section disposed with a sub- stantially horizontal flange fixed to the upper surfaces of the horizontal flanges of the carlines, and a substantially vertical flange upstanding from the inner edge of said hori- 95 zontal flange. The roof is thus divided lon- gitudinally into three sections, each section being adapted to be covered by an independ- ently formed, longitudinally extending, roof plate section; a central roof plate section 9 100 being disposed for covering the space be- tween the purlins, and side roof plate sec- tions 10—10 being disposed for covering the space between the purlins and the adjacent side plates 3.

The roof plate sections 10 have their oppo- site longitudinal edges fixed to the purlins 8, and to the side plates 3 respectively. The inner longitudinal edge of each of said roof plate sections is extended across the upper 105 surface of the horizontal flange of the adja- cent purlin and is bent into an upstanding flange 10^a fixed to the outer face of the up- standing flange of said purlin. The outer longitudinal edges of each of the roof plate 110

sections 10 is bent or flanged downwardly to correspond to the curvature of the carlines and is extended beyond the ends of said carlines and is fixed to the outer faces of the depending flange 5 of the adjacent side plate 3.

The central section of the roof is of inverted channel shape, the opposite longitudinal edges thereof being bent downwardly forming flanges 9^a. The flanges 9^a are fixed 10 to the outer faces of the respective flanges 10^a of the side roof plate sections 10 by through rivets extending through the upstanding flanges of the purlins. Intermediate its longitudinal edges the roof plate section 9 is preferably bowed upwardly from edge to edge for strengthening said plate.

At intervals along the length of the car are U shaped running board saddles as 11—11. These saddles span the roof plate section 9 and the opposite legs thereof depend and are fixed to the outer faces of the upstanding flanges of the purlins by rivets extending through the intermediate flanges 9^a 10^a of the roof plate sections. The usual 25 running boards as 12—12 are fixed to the upper surfaces of the saddles 11 and extend longitudinally above the section 9, being spaced therefrom. The lapping, substantially vertical, flanges of the plates 9 and 10 extending from end wall to end wall of the car, being rigidly fixed together throughout their length, materially assist the purlins in sustaining the roof against sagging intermediate its length. The posts 1 of the 30 car wall are preferably extended above the upper edge of the sheathing plates 2 and side plates 3 and are fixed to the depending flanges of the carlines, as at 1^a, for strengthening the connection between said carlines 35 and wall.

It will be observed that the central roof plate section 9 is spaced above the central portions of the carlines. At the end of the car said roof plate section is extended beyond the vertical plane of the end wall 2^a (see Fig. 4) and is curved downwardly as at 45 13 so as to lap the forward edge of the outstanding flange 14 of the end carline of the car. The bent portion 13 covers the flange 14 in such manner as to effectually prevent 50 the entrance of rain or sleet, but is spaced sufficiently from said flange so as to permit of the free passage of air into the car for ventilation.

55 What I claim is:

1. A car roof structure comprising a pair of roof plates extending longitudinally of the roof and being spaced upon opposite sides of the median line thereof, having upstanding substantially vertical flanges along their adjacent edges, a roof plate extending the length of said first mentioned plates formed with flanges disposed parallel with the flanges of said first mentioned plates

and fixed thereto, and an angled purlin containing one of said flanges. 65

2. A car roof structure comprising carlines, a pair of spaced roof plates extending substantially from end to end of the car in close proximity to said carlines and having marginal flanges extending throughout their length, a channel-shaped roof plate extending throughout the length of said first roof plates, said channel plate being spaced vertically above said carlines and connected to the carlines and to said spaced plates, angles fastened to said roof plates to strengthen the connection between said roof plates and channel plates, and running board supporting brackets connected with 80 said angles.

3. A car roof structure comprising a pair of side roof plates extending longitudinally of the roof and being spaced apart, having upstanding substantially vertical flanges 85 along one of their edges, a central roof plate extending the length of said first mentioned plates formed with pendant flanges lapping the vertical sides of said first mentioned flanges, and spaced purlins each having angled portions containing a flange of the side and a depending flange of the central roof plate. 90

4. A car roof structure comprising a pair of transversely spaced roof plates extending 95 substantially from end to end of the car having marginal flanges extending throughout their length and an interposed upwardly extending channel shaped roof plate extending throughout the length of said first 100 roof plates said interposed channel having flanges fastened to and lapping the flanges of said first plates for strengthening said first plates, and intersecting rolled sections connected to said flanges, said rolled sections and said lapping flanges being adapted to stiffen the same and to support saddles 105 for running boards.

5. In a car structure, the combination comprising carlines, spaced purlins, a pair 110 of spaced roof plates secured directly to said carlines and having right-angularly disposed upstanding flanges extending throughout the length of said purlins and being fixed thereto, and a second roof plate of inverted channel shape spaced vertically above 115 said carlines and having oppositely disposed depending flanges extending substantially the length of said first flanges and being fixed thereto and to the purlins, said inverted channel-shaped plate extending longitudinally beyond the pair of spaced plates and there being curved downwardly to provide a protected ventilating passage. 120

6. In a car roof structure, the combination comprising carlines, a pair of spaced roof plates, flanged purlins spaced apart, and an interposed inverted channel-shaped 125

- connecting roof plate extending to a higher plane than said spaced plates and having depending flanges lapping and being fixed to the flanges of said purlins, said connecting plate extending longitudinally beyond said carlines and bent downwardly at its end into the plane of the carlines to form a protected ventilator opening.
7. A car roof structure comprising a roof plate extending substantially from end to end of the car having marginal flanges extending throughout its length, a flanged roof plate extending throughout the length of said first roof plate having one of its flanges permanently fastened to one of the flanges of said first roof plate for strengthening said first plate, and an angled purlin containing within the angle the flanges of said flanged roof plates.
8. In a car roof structure, the combination comprising a pair of roof plates, flanged purlins spaced apart, and a channel shaped roof plate having flanges lapping and being fixed to the flanges of said purlins, and running board saddles fixed to the flanges of said purlins.
9. A car roof structure comprising a pair of parallelly disposed roof plates extending substantially from end to end of the car being spaced apart and having marginal flanges along their adjacent edges, said flanges extending substantially from end to end of the car, a channel shaped roof plate extending substantially from end to end of the car intermediate said first plates having flanges lapping and being fixed to the flanges of said first plates for strengthening said first plates, and running board saddles fixed to said flanges.
10. In a car roof structure, the combination comprising flanged purlins spaced apart, a channel shaped roof plate having flanges fixed to said purlins, and running board saddles fixed to said flanges.
11. A car roof structure comprising a pair of parallelly disposed spaced apart roof plates extending substantially from end wall to end wall of the car, a central roof plate section positioned above said roof plates, fastened thereto and extended beyond the end walls, said extended portion being bent to form an end ventilator.
12. In a car roof structure, the combination with a car end wall and side-plates, of a roof comprising carlines lapping and affixed to said side-plates, and roof plates some of which are secured to said side-plates, one of said roof plates being vertically spaced from said carlines and extending longitudinally beyond said end wall and spaced vertically and horizontally therefrom to form a ventilator for said car.
13. In a car roof structure, the combination with a car end wall, and a carline, of a roof plate spaced above and extending beyond said end wall and carline and being bent downwardly across the outer face of said end wall to form a ventilator for said car.
14. In a car roof structure, the combination with a car end wall, of flanged purlins spaced apart, a carline connecting said purlins, a channel-shaped roof plate spaced at its middle portion vertically away from the carline and fixed to said purlins at its edges and extending beyond the ends of the purlins and said end wall, and spaced vertically and horizontally from the end wall to form a ventilator for said car.
15. In a car roof structure, the combination comprising a plurality of carlines, purlins fixed to said carlines, roof plates fixed to said carlines having right-angularly disposed flanges fixed to said purlins, and an inverted channel shaped roof plate having flanges fixed to the flanges of said first mentioned plates.
16. In a car roof structure, the combination comprising a plurality of carlines, purlins fixed to said carlines, and a channel shaped roof plate spaced above said carlines having depending flanges fixed to said purlins.
17. In a box car roof, the combination with side walls comprising posts and sheathing plates fixed thereto and side plates extending longitudinally along the upper edges of said sheathing plates, of carlines extending across the upper edges of said sheathing plates being fixed to said side plates, and said posts being extended above said side plates and being fixed to said carlines.
18. In a car roof structure, the combination of carlines, spaced angular purlins, spaced side roof plates lapping the purlins and secured directly thereto and to the carlines, and an interposed inverted channel-shaped intermediate roof plate lapping the side roof plates and purlins and having its middle portion spaced vertically therefrom, said intermediate roof plate extending in downwardly bent extensions beyond the carlines longitudinally of the car, and an end wall coöperating with said intermediate plate to form a protected ventilator.
19. In a car construction, a side post, a side-plate supported from said post on the outer side of the post, the post extending relatively above the side-plate, a carline secured to said post and having a bent down end resting on a horizontal portion of the side-plate, and a roof sheet lapping the side-plate.
20. In a car structure, side posts, Z-shaped side-plates secured to said posts intermediate their ends, a carline secured to said posts and to said side-plate, and a roof sheet secured directly to flanges of said side-plates.

21. In a car construction, a side post, a flanged side plate supported on the outer side of the post below its upper end, a carline secured to the end portion of the post 5 and having a bent down end resting on said plate, and a roof plate supported by said carline and affixed to a flange of said plate.
22. In a car construction, a side post, a carline fastened to said post intermediate 10 its ends and extending beyond said side

post, a side plate having an outstanding web abutting the end of said carline, and having a depending flange and a roof plate affixed to said depending flange.

In witness whereof I have hereunto set 15
my hand in the presence of two witnesses.

VICTOR M. SUMMA.
